CLAIM

We claim the ornamental design for a television receiver, as shown and described.

DESCRIPTION

FIG. 1 is a front perspective view of a first embodiment of a television receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion in FIG. 1;

FIG. 10 is an enlarged view of the encircled portion in FIG. 2;

FIG. 11 is an enlarged view of the encircled portion in FIG. 3;

FIG. 12 is an enlarged view of the encircled portion in FIG. 5;

FIG. 13 is an enlarged view of the encircled portion in FIG. 6;

FIG. 14 is an enlarged view of the encircled portion in FIG. 7;

FIG. 15 is an enlarged view of the encircled portion in FIG. 8;

FIG. 16 is a front perspective view of a second embodiment of the television receiver showing our new design;

FIG. 17 is a front view thereof;

FIG. 18 is a rear view thereof;

FIG. 19 is a left-side view thereof;

FIG. 20 is a right-side view thereof;

FIG. 21 is a top view thereof;

FIG. 22 is a bottom view thereof;

FIG. 23 is a rear perspective view thereof;

FIG. 24 is an enlarged view of the encircled portion in FIG. 16;

FIG. 25 is an enlarged view of the encircled portion in FIG. 17;

FIG. 26 is an enlarged view of the encircled portion in FIG. 18;

FIG. 27 is an enlarged view of the encircled portion in FIG. 20;

FIG. 28 is an enlarged view of the encircled portion in FIG. 21;

FIG. 29 is an enlarged view of the encircled portion in FIG. 22;

FIG. 30 is an enlarged view of the encircled portion in FIG. 23;

FIG. 31 is a front perspective view of a third embodiment of the television receiver showing our new design;

FIG. 32 is a front view thereof;

FIG. 33 is a rear view thereof;

FIG. 34 is a left-side view thereof;

FIG. 35 is a right-side view thereof;

FIG. 36 is a top view thereof;

FIG. 37 is a bottom view thereof;

FIG. 38 is a rear perspective view thereof;

FIG. 39 is an enlarged view of the encircled portion in FIG. 31;

FIG. 40 is an enlarged view of the encircled portion in FIG. 32;

FIG. 41 is an enlarged view of the encircled portion in FIG. 33;

FIG. 42 is an enlarged view of the encircled portion in FIG. 35;

FIG. 43 is an enlarged view of the encircled portion in FIG. 37; and,

FIG. 44 is an enlarged view of the encircled portion in FIG. 38.

The short dash-dash broken lines in the figures showing portions of the television receiver form no part of the claimed design.

The dot-dot-dash broken lines encircling portions of the claimed design that are illustrated in enlargements form no part of the claimed design.
